TELEPHONE UNIT TEST SET

William Charles Hatfield and John Martin Reed, Garland,
Tex., assignors to Electronic Communications Services,
Inc., Garland, Tex.

Filed Jan. 20, 1971, Ser. No. 108,247

Term of patent 14 years

Int. Cl. D14—03

U.S. Cl. D26

FIG. 1

FIG. 2

FIG. 3

FIG. 4

FIG. 5

FIG. 6

FIG. 1 is a perspective view of a telephone unit test set showing our new design;

FIG. 2 is a top plan view of the telephone unit test set of FIG. 1;

FIG. 3 is a front elevational view of the telephone unit test set of FIG. 1;

FIG. 4 is a side elevational view of the telephone unit test set of FIG. 1;

FIG. 5 is a side elevational view of the opposite side of the telephone unit test set of FIG. 1 with the lid open; and

FIG. 6 is a top plan view of the telephone unit test set of FIG. 1 with the lid open.

We claim:

The ornamental design for a telephone unit test set, substantially as shown and described.
